UNITED STATES PATENT OFFICE.

JOHN O. KING, OF CARLISLE, KENTUCKY, AND NETTIE E. RUBERT, OF ALEDO, ILLINOIS.

MEAT-TENDERER.

No. 921,006.

Specification of Letters Patent.

Patented May 11, 1909.

Application filed April 29, 1908. Serial No. 429,953.

To all whom it may concern:

Be it known that we, JOHN O. KING and NETTIE E. RUBERT, citizens of the United States, residing at Carlisle, in the county of Nicholas and State of Kentucky, and Aledo, in the county of Mercer and State of Illinois, respectively, have invented certain new and useful Improvements in Meat-Tenderers, of which the following is a specification.

10 This invention relates to meat tenderers and particularly to that type in which are employed a plurality of perforating teeth along the contact edge.

15 An object of this invention is to provide for the construction of a device of this character that will withstand usage without becoming loose in any of its parts.

20 Another object of the invention is to provide for the forming of a guard or cleaner that may readily be detached from the teeth for the purpose of cleansing and sharpening the said teeth.

25 A still further object is to provide for the construction of a handle and the back of the device in one piece to insure rigidity and strength.

30 Other objects and advantages will be apparent from the following description and it will be understood that changes in the specific structure shown and described may be made within the scope of the claims and that any suitable materials may be used without departing from the spirit of the invention.

35 In the drawings forming a portion of this specification, and in which like numerals of reference indicate similar parts in the several views, Figure 1 is a side elevation of one of the faces of the device, Fig. 2 is a side elevation of the opposite face of the device, Fig. 3 40 is a top plan view, and Fig. 4 is a side elevation of Fig. 2 showing the guard detached from the teeth. Fig. 5 is a top plan view of the handle by which the device is adapted to be operated.

45 Referring to the drawings, 10 designates a blade having a plurality of teeth 11 formed in its cutting edge 12. The upper edge 13 of said blade 10 is reduced by means of the beveled ends 14 and 15. A metallic strip 16 50 is folded upon itself forming two sides 18 and 19 and is secured to the opposite faces of said blade 10 at the upper edge 13, said upper edge 13 being flush with the upper edges of the metallic strip 16. The free ends of the 55 metallic strips 16 are beveled to conform to the beveled end 14 of the blade 10. This

structure forms the back of the blade. The looped end 17 of said strip 16 is enlarged by the divergence of said sides 18 and 19 at the beveled end 15 and into the enlargement is 63 inserted a block 20 of wood or of any suitable material. This block 20 is secured by suitable rivets 21 between said sides for the purpose of forming a handle 32. To one end of said blade 10 are riveted two alining eye-bolts 22 positioned at the opposite beveled ends 14 and 15 near the back 16. Hinged in these eye-bolts 22 is a spring 23 which supports and actuates a guard or cleaner 24 as hereinafter described. The spring 23 comprises a rod passed through the eye-bolts 22 to form a top-member 25, the rod having its end portion beyond the eye-bolts 22 bent inwardly and downwardly as shown at 26, to approach a point centrally of the top 75 member 25, as shown at 26', said ends then diverging to the opposite ends 14 and 15 of said blade 10 where they extend downward and terminate in the eyes 27 formed in the opposite ends of the guard 24. The 80 inner ends of the inwardly extending portion of said spring 23 are held in position by a link 28. The guard or cleaner 24 consists of a metallic plate 31 slidably engaging one face of said blade 10, one edge 29 of which 85 extends below the teeth 11 and is held against said face by lugs 30, said lugs 30 being formed integral with the ends of said guard 24. The ends of the guard 24 are split so that one section thereof may be used 90 as a lug, for engaging the opposite ends of the blade 10.

In operating the device the handle 30 is grasped and the meat is pounded in an ordinary manner. In the act of pounding the 95 guard 24 first engages the meat but by its resilient support 23 yields and the teeth 11 are brought into action. When the device is raised preparatory to another blow the spring 23 forces the guard or cleaner downwardly past the teeth 11 carrying any material which had adhered to the teeth 11. By the use of this guard the teeth 11 are kept free from particles of meat which would otherwise in a short time clog up the teeth 100 and prevent the proper carrying out of their functions.

If it is desired to cleanse the teeth 11 the guard 24 may be removed by drawing the same downwardly against the tension of the spring 23 until the lugs 30 are disengaged from the blade 10 when the guard may swing 110

laterally, by reason of its connection to the spring 23 which is pivotally mounted in the eye-bolts 22.

What is claimed is:

- 5 1. A device of the class described comprising a handle, a blade supported by said handle, teeth on the lower edge of said blade, a guard slidably mounted on one face of said blade, lugs carried at the ends of said guard, 10 and passing over the ends of said blade and engaging the opposite face thereof, and a spring hinged to said blade and connected with said guard.
- 15 2. A device of the character described comprising a handle, a blade, eye-bolts on said blade, a guard on said blade, and a spring carried by said eye-bolts and con-

nected with said guard, said spring comprising a rod passing through said eye-bolts, said ends being bent backwardly and then divergently to the sides of said blade, and then extending downwardly and engaging said guard, and a link engaged with the inner ends of said backwardly bent portion.

In testimony whereof we affix our signatures, in presence of two witnesses.
